(57) **CLAIM**

The ornamental design for a multi-function key-shaped tool, as shown and described.

DESCRIPTION

FIG. 1 is a first perspective view of the multi-function key-shaped tool;

FIG. 2 is a second perspective view of the multi-function key-shaped tool of FIG. 1;

FIG. 3 is a right side view of the multi-function key-shaped tool of FIG. 1;

FIG. 4 is a left side view of the multi-function key-shaped tool of FIG. 1;

FIG. 5 is a top view of the multi-function key-shaped tool of FIG. 1;

FIG. 6 is a bottom view of the multi-function key-shaped tool of FIG. 1;

FIG. 7 is a front view of the multi-function key-shaped tool of FIG. 1; and,

FIG. 8 is a back view of the multi-function key-shaped tool of FIG. 1.
